DANDELION AND WEED PULLER

Clarence A. Banta, Alamosa, Colo.

Application April 12, 1941, Serial No. 388,327

5 Claims. (Cl. 294—50.9)

The present invention relates to improvements in garden implements and pertains more particularly to an implement for pulling weeds, such as dandelions and the like from a lawn.

The primary object of the invention is to provide a dandelion and weed puller that is simple in construction, efficient in operation, relatively inexpensive to manufacture, and comprising a minimum number of moving parts rendering unlikely damage other than resultant from ordinary use.

A further object of the invention is to provide a dandelion and weed puller comprising an elongated handle member having attached to its lower end a swingable gripping jaw actuated by pressing the handle in the lawn and releasing the same therefrom, whereby the user of the implement may stand in an upright position when removing dandelions and similar weeds from a lawn.

The invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a perspective view of a dandelion and weed puller constructed in accordance with the present invention.

Figure 2 is a vertical sectional view thereof.

Referring more in detail to the accompanying drawing, the improved dandelion and weed puller is generally designated by the reference numeral 5 and includes an elongated shaft 6 of a length that will permit the user of the device to stand in an upright position when removing dandelions and similar weeds from a lawn. The lower end 7 of the shaft 6 is slightly smaller in diameter than the main portion of the shaft and said end is formed with a slot 8 within which is pivotally mounted an arcuate-shaped arm 9, said arm being attached within the slot by means of a pin or the like 10.

A metal sleeve 11 is fixedly secured to and forms a part of the lower end of the shaft 6, said sleeve conforming in shape to the reduced end 7 to provide a shoulder portion 12. A slot 13 is formed in the sleeve 12 through which the arcuate-shaped arm projects. As more particularly shown in Figure 2 of the drawing, the sleeve 11 extends below the shaft 6, the lowermost end of

the shaft resting upon opposed flanges 14 struck out and bent inwardly from the sleeve. By this construction, the shaft 6 and sleeve 11 move in unison as the implement is actuated for removing dandelions and similar weeds.

The lower end of the sleeve 11 is slidably disposed in a cylinder 15, said cylinder being formed with a slot 16 complementary to the slot 13. One wall of the lowermost end of the cylinder 15 is bent inwardly as indicated at 17 and has formed on the area which extends parallel to the rear wall 18, a serrated tooth-like portion 19. The rear wall 18 projects below the teeth 19 and is formed with penetrating prongs 20, the prongs 20 adapted to be pushed into the lawn when using the implement as will be hereinafter described.

A coil spring 21 is mounted within the sleeve 11, one end 22 thereof in engagement with the lower end of the shaft 6 while the other end 23 contacts the curved portion 17 of the cylinder 15. The shaft 6 and its sleeve 11 are urged downwardly within the cylinder 15 against the tension of the spring 21 to actuate the arm 9, and upon release of pressure on the shaft, said spring will return the same to normal position.

The free end of the arm 9 is slotted as indicated at 24 and supports therein a plate 25 having teeth 26 formed on one edge thereof. The plate 25 is held within the slot by means of a cotter key or the like 27 and the teeth of said plate cooperate with the teeth 19 for pulling weeds from the lawn.

In the use of the implement, the end of the shaft 6 will be engaged and the prongs 20 pushed into the ground within the area of the dandelion or weed to be removed. As the shaft 6 is pushed downwardly, it moves within the cylinder 15 until the shoulder 12 abuts the upper end of the cylinder causing the arm 9 to swing outwardly on its pivot 10 to the position shown in Figure 1 of the drawing. The release of pressure on the shaft 6 will permit the spring 21 to return said shaft to its normal position and the upward movement thereof will swing the arm 9 into the closed position shown in Figure 2 whereupon the dandelion or similar weed will be held between the teeth 19 and 26. An upward pull on the shaft to disengage the prongs 20 will remove the dandelion or similar weed held between the teeth.

Thus it will be seen that there has been provided an implement that will effectively remove weeds such as dandelions and the like in an easy and rapid manner while permitting the user thereof to remain in an upright position at all

times. The implement comprises a minimum number of moving parts rendering unlikely damage other than resultant from ordinary use.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed is:

1. A garden implement of the character described comprising an elongated shaft, a cylinder for slidably receiving the lower end of said shaft, an arcuate-shaped arm pivotally mounted in the lower end of said shaft, said shaft and cylinder having aligned slots through which the intermediate portion of said arm extends, a gripping jaw carried on the free end of said arm, and a serrated portion formed on the lower end of said cylinder cooperating with said gripping jaw to extract weeds upon the actuation of said shaft.

2. A garden implement of the character described comprising an elongated shaft, the lower end of said shaft having a slot formed therein, a metal sleeve fixedly secured to the lower end of said shaft, a cylinder for slidably receiving said sleeve, an arcuate-shaped arm pivotally mounted in said shaft slot, said sleeve and cylinder having aligned slots through which the intermediate portion of said shaft extends, a gripping jaw carried on the free end of said arm, and a serrated portion formed on the lower end of said cylinder cooperating with said gripping jaw for removing weeds upon the actuation of said shaft.

3. A garden implement of the character described comprising an elongated shaft, a sleeve fitted to the lower end of said shaft, a cylinder for slidably receiving said sleeve, one wall of the lower end of said cylinder curved into appressed relation with the other wall to form a relatively closed end for said cylinder, an arcuate-shaped

arm pivotally mounted in the lower end of said shaft, said shaft and cylinder having aligned slots through which the intermediate portion of said arm extends, a gripping jaw carried on the free end of said arm, and a serrated portion formed on the closed end of said cylinder cooperating with said gripping jaw for removing weeds upon the actuation of said shaft.

4. A garden implement of the character described comprising an elongated shaft, a sleeve fitted to the lower end of said shaft, a cylinder for slidably receiving said sleeve, one wall of the lower end of said cylinder curved into appressed relation with the other wall to form a relatively closed end for said cylinder, an arcuate-shaped arm pivotally mounted in the lower end of said shaft, said shaft and cylinder having aligned slots through which the intermediate portion of said arm extends, spring means held within said cylinder having one end in contact with the lower end of said shaft and its other end in contact with the lower end of said cylinder, a gripping jaw carried on the free end of said arm, and a serrated portion formed on the closed end of said cylinder cooperating with said gripping jaw for extracting weeds on the actuation of said shaft, said spring being adapted to return said shaft to normal position upon the release of pressure thereon.

5. A garden implement of the character described comprising an elongated shaft, a sleeve fitted to the lower end of said shaft, a cylinder for slidably receiving said sleeve, one wall of the lower end of said cylinder curved into appressed relation with the other wall to form a relatively closed end for said cylinder, an arcuate-shaped arm pivotally mounted in the lower end of said shaft, said shaft and cylinder having aligned slots through which the intermediate portion of said arm extends, a gripping jaw carried on the free end of said arm, a serrated portion formed on the closed end of said cylinder cooperating with said gripping jaw for removing weeds upon the actuation of said shaft, and ground penetrating means formed integral with and extending from said cylinder.

CLARENCE A. BANTA.
